BASE FOR SANCTUARY LAMP OR MASS CARD HOLDER

Ralph H. Ellsworth, Willoughby, Ohio, assignor to Superior Funeral Supply Corporation, Cleveland,
Ohio, a corporation of Ohio

Filed Jan. 16, 1969, Ser. No. 15,374

Term of patent 14 years

Int. Cl. D26—02

U.S. Cl. D48—20

The figure is a perspective view of a base for sanctuary lamp or mass card holder embodying my new design, the opposite sides not shown, being substantially mirror images of the sides shown.

I claim:

The ornamental design for a base for sanctuary lamp or mass card holder, as shown and described.
